UNITED STATES PATENT OFFICE.

MICHAEL CROUGH, OF ILION, NEW YORK.

SAFETY RAZOR.

Application filed May 24, 1923. Serial No. 641,122.

To all whom it may concern:

Be it known that I, MICHAEL CROUGH, a citizen of the United States, residing at Ilion, in the county of Herkimer and State of New York, have invented new and useful Improvements in Safety Razors, of which the following is a specification.

This invention relates to safety razors, and one object of my invention is to provide a razor which is simple of construction and composed of but a few parts, admitting of its manufacture at a low cost and at the same time adapting the razor to be easily cleaned and maintained in a sanitary condition.

Another object of the invention is to provide a razor the working portion of which is of sufficiently narrow width to adapt it to be employed for shaving portions of the face which are difficult or impossible to reach with safety razors of ordinary construction.

Still another object of the invention is to provide a razor which will permit of the use of blades which may be continuously sharpened and used until worn out.

With these and other objects in view, the invention consists of the features of construction, combination and arrangement of parts, hereinafter fully described and claimed, reference being had to the accompanying drawing, in which:—

Figure 1 is a perspective view of a safety razor embodying my invention.

Figure 2 is a central vertical transverse section through the same.

Figure 3 is a longitudinal section on the line 3—3 of Figure 2.

Figure 4 is a fragmentary perspective view of the comb plate.

In the practical embodiment of my invention, I provide a safety razor comprising a handle 1 having at one end a milled or serrated grip portion 2 and carrying at its opposite end a comb plate 3. This comb plate 3 extends at an oblique angle to the end of the handle to which it is applied and is suitably secured to the handle, as by providing said comb plate with an opening receiving a reduced portion of the handle which is upset or riveted thereto, as indicated at 4, whereby said parts are firmly fastened together. The fastening connection 4 is arranged at a point between the longitudinal center of the comb plate and its rear edge, the major portion of the comb

plate thus extending forwardly and at an outward and downward substantially oblique angle to the plane of the handle.

The forward edge of the comb plate is slotted to provide the spaced comb teeth 5 having the downturned guard fingers 6, and the upper surface of said plate is designed to serve as a seat support for the razor blade 7. This blade 7 is designed to rest flatly upon the comb plate and has its upper and lower faces beveled at its forward portion to form a cutting edge 8 designed, when the blade is applied for use, to extend over the comb teeth and the spaces between the same for cooperation therewith in the usual way.

The comb plate 3 is provided at its opposite ends with inturned flanges 9 which extend inwardly a short distance and overlie the upper surface of said comb plate. These flanges serve as blade retainers, adapted to overlie the end edges of the blade, and forming grooves 10 between the same and the body of the comb plate to receive such end edges of the blade. These grooves are open at their upper or rear ends, in line with the rear edge of the comb plate, to adapt the blade to be slidably inserted and removed and are closed at their lower or forward ends to limit the forward movement of the blade and to prevent it from sliding forwardly beyond a proper working position. To this end the forward portions of the flanges 9 are bent downwardly against the upper face of the comb plate 3, as indicated at 11, forming stops against which the extremities of the cutting edge of the blade may bear to arrest the forward sliding movement of said blade when the cutting edge is in accurate cutting position and relation to the comb teeth 5. The said downwardly bent portions 11 of the flanges 9 are preferably curved so as to form auxiliary guard portions adapted to run easily over the face of the user in the operation of the razor.

The forward portions of the flanges 9 may be comparatively narrow or of restricted width, but the rear portions thereof, in rear of the central longitudinal line of the comb plate, are widened as indicated at 12, so as to provide abutment shoulders 13 in the length of the flanges. These abutment shoulders are adapted to be engaged by the end portions of the rear edge of a clamping plate 14, employed to clamp the cutting edge of the blade 7 firmly down against the comb

plate 3 and to hold said blade against any possibility of recession or rearward displacement. This clamping plate 14 is of oblong rectangular form and its end edges are designed to bear against the sides of the narrower front portions of the flanges 9 and the forward edge of the upper surface of said clamping plate is beveled, as indicated at 15, so as to form a guard or guide surface immediately in rear of the cutting edge of the plate, which guide or guard surface will also ride smoothly over the face of the user in shaving and permit of the smooth and easy operation of the device in its shaving action.

The clamping plate 14 is made of spring metal and is provided with a central shank 16 which extends rearwardly over the blade and comb plate and has a hooked portion 17 to extend around and under the rear edges of the blade and comb plate and in proximity to the rear surface of the handle 1. This hooked portion 17 terminates in a transversely curved latch member 18 having a forwardly projecting locking tongue 19 to engage a locking recess 20 in the rear side of the handle whereby the clamping plate is adapted to be drawn against the shoulders 9 and engaged with the handle to secure said clamping plate in clamping position.

The forward portion of the body of the clamping plate having the beveled surface 15 is depressed with relation to the body portion of said plate, so that said forward portion will bear against the blade 7 adjacent to the cutting edge of the latter, while the body portion of the plate 14 and its shank 16 will lie above and in spaced relation to the blade, as particularly shown in Figure 2. By this means the rear edge of the plate 14 may be engaged with the shoulders 13 and the shank 16 and hooked portion 17 thereof depressed to draw the blade against said shoulders 13 and at the same time cause the spring tongues 19 to snap lock into the locking recess 20, the clamping plate thus being held under spring tension and in locking engagement with the shoulders 13 and recess 20 to maintain said plate and the blade firmly in working position. By, however, exerting pressure upon the hooked portion 17, the tongue 19 may be depressed out of locking engagement with the recess 20, allowing the clamping plate to be released and lifted off in an easy and convenient manner to permit of the adjustment or removal of the blade or cleansing of the parts in a thoroughly sanitary manner as occasion requires in the use of the razor.

In practice, the comb plate is made comparatively narrow and set at such an angle as to admit of the use of a comparatively narrow blade, the angular arrangement of

the comb plate 3 and of the blade, and their narrow width, adapting the razor to be used in a ready and convenient manner in order to shave all portions of the upper lip or other angular portions of the face without interference from the nose or other portions of the face liable to interfere in the use of ordinary razors, so that any point upon the face may be reached and readily shaved. The mode of retaining the blade in position also adapts the blade to be continuously sharpened and used until narrowed to such a degree by repeated sharpening that it may be discarded as worthless. This results from the fact that the grooves 10 will firmly retain the edges of the blade, while the clamping portion of the clamping plate is set to engage a restricted portion of the blade immediately in rear of its cutting edge, allowing the blade to be reduced by successive sharpenings until it is very narrow without impairing the plate clamping action. In practice the distance between the inner side walls of the grooves 10 may slightly exceed the length of the blade to be used, allowing the blade to be adjusted or set at a slight angle. This permits an adjustment of the blade so that its cutting edge may be brought into proper working alignment along the comb surface of the comb plate at times when, in a honing or sharpening action, the edge of the blade may not be sharpened in an accurate longitudinal line, the clamping plate firmly holding the otherwise loosely held blade against any possibility of displacement.

The mode of use of the razor will, it is thought, be readily understood from the foregoing description, and it will be seen that the invention provides a simple type of razor including blade supporting and clamping means which may be manufactured at a comparatively low cost, and which provides for the secure holding of a blade under all conditions and the ready and easy assembly of the parts for use and their disassembly for storage, repairs, cleaning or other purposes. Also it will be seen that the construction described adapts a blade of very narrow width to be inserted for use and clamped in position, so that a blade of initially greater width may be continuously sharpened, and used until reduced by sharpening to a material degree, ensuring economy in the use of the blades.

Having thus fully described my invention, I claim:

A safety razor comprising a handle having a locking recess, a comb plate carried by the handle and provided with inturned flanges at its side edges forming retaining grooves to slidably receive the end edges of a razor blade, said flanges having widened portions forming inwardly extending shoulders, a spring metal clamping plate having

a rear portion normally lying out of contact with the blade and movable toward and from the same and adapted to bear at its rear edge against said shoulders, said plate 5 having a down bent or relatively depressed forward portion to engage the blade in rear of the cutting edge of the latter, and a central shank carried by said rear portion of the blade and curved to extend around the rear edges of the blade and comb plate and beneath the same and having a terminal locking tongue to interlock with said recess in the handle. 10

In testimony whereof I affix my signature.

MICHAEL CROUGH.
